DESIGN FOR AN ERASER TIP FOR PENCILS

Horace B. Van Dorn, Maplewood, N. J., assignor
to Joseph Dixon Crucible Company, Jersey
City, N. J., a corporation of New Jersey

Application December 14, 1933. Serial No. 50,067

Term of patent 14 years

To all whom it may concern:

Be it known that I, HORACE B. VAN DORN, a citizen of the United States, and a resident of Maplewood, in the county of Essex and State of New Jersey, have invented a new, original, and ornamental Design for Eraser Tips for Pencils, of which the following is a specification, reference being had to the accompanying drawing, forming a part thereof and in which:

Fig. 1 is a front and rear elevation,
Fig. 2 is a side elevation, and
Fig. 3 is a top plan of an eraser tip for pencils
embodying my new design.

I claim:—

The ornamental design for an eraser tip for pencils, as shown.

HORACE B. VAN DORN.
